UNITED STATES PATENT OFFICE.

HARRY D. LATHROP AND WALTER H. PAULSON, OF CHICAGO, ILLINOIS.

FEEDING MECHANISM FOR CAN-WASHING MACHINES.

1,249,130.

Specification of Letters Patent. Patented Dec. 4, 1917.

Application filed February 16, 1917. Serial No. 149,101.

To all whom it may concern:

Be it known that we, HARRY D. LATHROP and WALTER H. PAULSON, citizens of the United States, and residents of the city of Chicago, county of Cook, and State of Illinois, have invented certain new and useful Improvements in Feeding Mechanism for Can-Washing Machines, of which the following is a specification.

- 10 Our invention relates to improvements in milk can washing machines, and has for its object the production of improved means for controlling the feeding of the milk cans and covers through the machine.
- 15 A further object is the production of a machine, as mentioned, which will be of durable and economical construction and efficient in use.

Other objects will appear hereinafter.

20 The invention consists in the combinations and arrangements of parts hereinafter described and claimed.

The invention will be best understood by reference to the accompanying drawings forming a part of this specification, and in which,

Figure 1 is a side elevation of a can washing machine embodying the invention,

Fig. 2, a fragmental detail illustrating the can arresting mechanism employed at the discharge end of the machine,

Fig. 3, a partially sectional side elevation of the inlet or entrance end of the machine, showing the opposite side of the machine from that disclosed in Fig. 1,

Fig. 4, a section taken on substantially line 7—7 of Fig. 3,

Fig. 5, a section taken on substantially line 8—8 of Fig. 3,

40 Fig. 6, a section taken on substantially line 9—9 of Fig. 5,

Fig. 7, a section taken on substantially line 10—10 of Fig. 3, and

Figs. 8 and 9, sections taken on substantially lines 11—11 and 12—12 of Fig. 1.

The preferred form of construction, as illustrated in the drawings, comprises a suitable supporting frame 15 in the lower portion of which are mounted spaced centrally positioned longitudinally extending guide rails 16, adapted to constitute a guide for the milk cans A which are adapted to be slid along said guide rails in the washing or cleansing operation. Correspondingly mounted in the upper end of the frame 15 are spaced centrally positioned longitudi-

nally extending guide rails 17 adapted to constitute a guide for the covers B of the milk cans in the cleansing of said covers as hereinafter set forth.

60

For the feeding or pushing of the cans A along the guide rails 16, a feeding device is provided comprising elongated bars 18 which are arranged between the guide rails 16 and freely slidable independently

65

thereof, as seen in the several views. To alleviate friction, rollers 19, as seen in Fig. 5, may be employed to support the bars 18 in the sliding or reciprocatory movement of the same. Spaced along the bars 18 are 70 pairs of engaging pawls 20 pivotally connected therewith at 21. Said pawls 20 are adapted normally to assume positions, as indicated in Fig. 6, in which the forward ends thereof project above the upper edges 75

of the guide rails 16 for engagement with the cans A arranged upon said guide rails, as clearly seen in Fig. 6. Downward rocking of the rearward ends of pawls 20 is limited by stops 22 fixed to bars 18, as seen in 80

Fig. 6. The arrangement is such, as will be seen, that during reciprocation of the feed bars 18, the pawls 20 in the forward movement of said feed bars will engage

with the cans A and cause the same to be 85 slid or advanced along the guide rails 16. In the rearward movement of the bars 18,

the pawls 20, because of the pivotal mounting thereof, will yield downwardly so as to 90 pass under the cans in order to position each pair of said pawls, upon each return move-

ment of the same, behind the next rearward can. The amplitude of reciprocation of the feeding mechanism is greater than the width 95

of the cans, so that, with this arrangement, it is apparent that upon each reciprocation of the feeding mechanism, the cans will be

stepped or pushed forward a predetermined distance. Moreover, the cans are individu- 100

ally engaged, so that one can, or any number of cans, may be intermittently pushed or fed through the machine through recipro- 105

catory movement of the feeding mechanism. Likewise the can covers B are fed through the machine through the medium of a mech- 110

anism of a like construction, the same comprising reciprocatory bars 23 arranged be- 115

tween the guide rails 17, said feed bars car- 120

rying pawls 25 pivotally mounted at 26 upon said feed bars. Stops 27 coöperate with 125

pawls 25 to limit downward movement of the rearward ends thereof. The operation

of this feeding mechanism coöperating with the can covers is precisely the same as that used in connection with the milk cans before described. The two feeding mechanisms are 5 connected together for simultaneous operation by means of connecting bars 28 which rigidly connect the rearward ends of feed bars 18 and 23, as seen in Figs. 1, 3 and 7.

Said feeding mechanism is manually operated 10 through the medium of an oscillatory lever 29 fulcrumed at 30. From the fulcrumed end of said lever projects an integral arm 31 which is connected at its upper end by means of a link 32 with a rocker arm 33 15 pivotally connected at 34 with the frame 15. The upper end of arm 33 is connected with an arm 35 which is pivotally mounted in a carriage 36 slidably mounted between guide bars 37, as clearly seen in Figs. 3 and 7, arm 20 35 being also connected at its inner end with bars 28 which connect the can cover feeding mechanisms. The arrangement is such, as will be seen, that reciprocation or actuation 25 of the feeding mechanism of the machine may be effected by simply oscillating the lever 29.

In order to hold the can covers in the positions to which the same are advanced with each reciprocation of the feeding mechanism 30 coöperating therewith, a series of plates or leaves 38 are provided, arranged above the cover guide and pivotally connected at their rearward ends by means of crank or offset spindles 39 with rigid frame bars 40 at the 35 upper end of the machine. The arrangement is such that the members 38 normally assume an inclined position in the direct path of the can covers. As said covers are moved along the cover guide, said members 40 38 frictionally engage against the upper sides thereof, as clearly seen in Fig. 6, serving to hold the same against relative movement upon return sliding of the can feeding mechanism, as will be readily understood. 45 The employment of a crank or offset spindle for connecting the members 38 with the frame of the machine, of course allows for relative vertical adjustment of the pivotal axes, thereby permitting said members to 50 always assume positions resting flatly against the upper sides of the covers. The under sides of plates 38 are of channel form, whereby said plates serve as keepers to hold the covers centrally upon the guide rails 17.

55 In the travel of the milk cans along the guide rails 16, the same are in an inverted position, as seen in the several views, said cans, when the same reach the discharge ends of said guide rails, being pushed therefrom by the feeding mechanism on to a rockingly mounted reversing member 41 which serves to automatically reverse each can and deliver the same onto an inclined discharge chute 42 where the covers of the cans are 60 applied to the latter, after which the same

are completely discharged from the machine. This reversing and cover-applying mechanism, however, is not claimed in this application and therefore no detail description is here given. However, in order to absolutely 70 arrest the movement of each can before the same reaches the discharge ends of the guide rails 16, in order to prevent premature discharge of the same into the reversing device 41, a stop or arresting member 43 is provided, as seen in Figs. 2 and 8. The member 43 is arranged centrally between the guide rails 16, adjacent the discharge ends thereof, said member being pivotally mounted at 44 in stationary supporting arms 44' 75 80 which are rigidly connected with a suitable or convenient portion of the frame work of the machine.

In order to retain the cans and covers centrally upon the guide rails 16 and 17, side 85 bars 78 and 79 are preferably employed, as clearly shown in Fig. 8.

With the construction as set forth it will then be seen that in the operation of the same, it is only necessary for the operator to 90 place the cans and covers into the machine at one end of the same. This having been done the lever 29 needs only to be oscillated to effect the intermittent feeding of the can through the machine. Where a large number of cans are to be cleaned a can will be inserted after each complete oscillation of the handle, the cans thus inserted proceeding through the machine in the manner illustrated in Figs. 3 and 6. To aid in the proper 95 positioning of the cans and covers on the respective guide rails, upon insertion of the same into the machine, stationary stops 20' and 25' are provided as seen in Figs. 3, 4 and 5. In the passage of the same through 100 the machine, each can is successively subjected to the washing, sterilizing and drying action as above described.

While we have illustrated and described the preferred form of construction for carrying our invention into effect, this is capable of variation and modification without departing from the spirit of the invention. We, therefore, do not wish to be limited to the precise details of construction set forth, but desire to avail ourselves of such variations and modifications as come within the scope of the appended claims.

Having described our invention what we claim as new and desire to secure by Letters Patent is:

1. A machine of the class described comprising a guide for the objects to be cleaned; feeding means for intermittently moving the objects along said guide; means for temporarily arresting the forward movement of an object at a position to which the same is moved by said feeding means, said arresting means comprising a movably mounted normally inoperative member adapted to

obstruct the path of an object mounted for travel on said guide; and means for automatically locking said arresting member in operative position upon advance of the 5 object on said guide, substantially as described.

2. A machine of the class described comprising a guide for the objects to be cleaned; reciprocatory feeding means for intermittently moving the objects along said guide, said feeding means being operative in only one direction of movement thereof, the return movement of said means being idle; means for temporarily arresting the forward movement of an object at a position to which the same is moved by said feeding means, said arresting means comprising a movably mounted normally inoperative member adapted to obstruct the path of an object mounted for travel on said guide; and means for locking said arresting member in operative position as said feeding means reaches its forward terminal of movement and releasing said member upon return movement of said feeding means, substantially as described.

15 3. A machine of the class described comprising a guide for the objects to be cleaned; feeding means for intermittently moving the objects along said guide; means for temporarily arresting the forward movement of an object at a position to which the same is moved by said feeding means, said arresting means comprising a pivotally mounted normally inoperative member adapted to obstruct the path of an object mounted for travel on said guide; and means for automatically locking said arresting member in operative position upon advance of the object on said guide, substantially as described.

20 4. A machine of the class described comprising superposed can and cover guides; means for individually and intermittently moving said cans and covers simultaneously along said guides, said means comprising two series of reciprocatory spaced engaging devices adapted for engagement with the cans and covers; and a rigid connection between said series of engaging devices for effecting unisonous movement thereof, substantially as described.

25 5. A machine of the class described comprising superposed can and cover guides; means for individually and intermittently moving said cans and covers simultaneously along said guides, said means comprising two series of reciprocatory spaced engaging devices adapted for engagement with the cans and covers; reciprocatory elements carrying said engaging devices; and means for extending between and rigidly connecting said elements for effecting unisonous movement thereof, substantially as described.

effecting unisonous movement thereof, substantially as described.

6. A machine for cleansing milk cans and the covers therefor, comprising superposed can and cover guides; means for individually and intermittently moving said cans and covers simultaneously along said guides, said means comprising two series of reciprocatory spaced engaging devices adapted for engagement with the cans and covers; and an operative connection between said series of engaging devices for effecting unisonous movement thereof, substantially as described.

7. A machine for cleansing milk cans and the covers therefor, comprising superposed can and cover guides; means for individually and intermittently moving said cans and covers simultaneously along said guides, said means comprising two series of reciprocatory spaced engaging devices adapted for engagement with the cans and covers; and an operative connection between said series of engaging devices for effecting unisonous movement thereof, substantially as described.

8. A machine of the class described comprising a guide for the objects to be cleaned; means for individually and intermittently moving the objects along said guide; and pivotally mounted members arranged for rocking in a vertical plane, adapted for engagement against the upper sides of the objects mounted upon said guide for yieldingly holding said objects in positions to which the same are advanced in the operation of said last mentioned means, the under sides of said members being channel-formed to receive the upper portions of said objects, substantially as described.

In testimony whereof we have signed our names to this specification in the presence of two subscribing witnesses.
